UNITED STATES PATENT OFFICE.

JOHN H. HORN, OF PATERSON, NEW JERSEY, ASSIGNOR TO THE NATIONAL LOCK WASHER COMPANY, OF NEWARK, NEW JERSEY, A CORPORATION OF NEW JERSEY.

NUT-LOCK.

1,135,284.

Specification of Letters Patent. Patented Apr. 13, 1915

Application filed November 30, 1914. Serial No. 874,709.

To all whom it may concern:

Be it known that I, JOHN H. HORN, a citizen of the United States, residing at the city of Paterson, Passaic county, State of New Jersey, have invented certain new and useful Improvements in Nut-Locks; and I do declare the following to be a full, clear, and exact description of the invention, such as will enable others skilled in the art to 10 which it appertains to make and use the same.

This invention has reference to nut locks, which are in the general form of segments of a helical coil of suitable metal, and the object of the invention is to increase the 15 resistance afforded by the nut locks against the clamping elements.

In the accompanying drawing Figure 1 is a plan view of the nut lock—Fig. 2 an 20 edge elevation of the nut lock looking toward the extremities of the segment—Fig. 3 an edge elevation of the nut lock when viewed from a point at right angles from that of Fig. 2, and Fig. 4 is an edge elevation of the nut lock viewed from a point 25 directly opposite to that of Fig. 3.

Similar numerals of reference denote like parts in the several figures of the drawing.

In the present invention portions of the 30 helical segment of the nut lock are bent or displaced transversely by slightly twisting certain portions of the entire body of the helical segment about an axis which extends along the length of the spiral curve so that 35 such portions are displaced out of the normal curvature of the helical segment.

The new spiral curves of the twisted portions have a pitch different from that of the 40 original helical segment, and, of course, the surfaces of the twisted portions are all at an angle to the surfaces of the original helical

segment. Preferably this twist is formed in two oppositely disposed portions of the helical segment and in such case the twisting is preferably effected in reverse directions, but 45 this invention is not limited to this detail.

Referring to the accompanying drawing, the numeral 1 is used to designate the nut lock generally speaking, 2 designates the inner edge of the helical segment, 3 designates the outer edge thereof, and 4 designates the portions that are twisted.

What is claimed is:—

1. A nut-lock, consisting in general form of a segment of a helix, having certain portions twisted about an axis extending lengthwise of the helical segment. 55

2. A nut-lock of helical form, each end of the nut-lock being twisted or tilted, in the direction of its width, out of line with the normal surface of the helix. 60

3. A nut-lock of helical form, each end being twisted transversely, in the direction of its width, out of line with the normal helical surface and having a pitch different 65 from that of the adjacent body portion.

4. A nut-lock of helical form, having that portion of the body adjacent each end twisted transversely, in the direction of its width, out of line with the normal surface of the 70 helix, the twist in one end being in a direction the reverse of that in the other.

5. A nut-lock of helical form, having a portion of the body twisted or tilted, in the direction of its width, out of line with the 75 normal surface of the helix.

In testimony whereof I affix my signature in presence of two witnesses.

JOHN H. HORN.
